We claim the ornamental design for a skin therapy light, as shown and described.

DESCRIPTION

FIG. 1 is a top perspective view of a skin therapy light, showing our new design;

FIG. 2 is a bottom perspective view thereof;

FIG. 3 is a front elevation view thereof;

FIG. 4 is a back elevation thereof;

FIG. 5 is a top plan view thereof;

FIG. 6 is a bottom plan view thereof;

FIG. 7 is a right-side elevation view thereof; and,

FIG. 8 is a left-side elevation view thereof, showing the skin therapy light.

The broken line showing of the PEMF (Pulsed ElectroMagnetic Field) units depicts portions of the skin therapy light and forms no part of the claimed design.
